UNITED STATES PATENT OFFICE.

MAX CASPARI, OF DETROIT, MICHIGAN.

HORSESHOE.

SPECIFICATION forming part of Letters Patent No. 295,616, dated March 25, 1884.

Application filed December 12, 1883. (No model.)

To all whom it may concern:

Be it known that I, MAX CASPARI, of Detroit, in the county of Wayne and State of Michigan, have invented new and useful Improvements in Horseshoes; and I do hereby declare that the following is a full, clear, and exact description thereof, reference being had to the accompanying drawing, which forms a part in this specification.

10 This invention relates to an improvement in horseshoes; and the invention consists in the peculiar construction of the sole of the shoe, whereby the necessity of calks is obviated.

15 In the drawing which accompanies this specification my improved horseshoe is shown in perspective, with a part taken away to show its cross-section.

A is a horseshoe, made of steel, and may be 20 in the usual shape, or with the inside and outside walls tapering toward the calk-lines, as shown; but upon the sole of the shoe are formed two like ridges, *a b*, which follow the inner and outer contour of the shoe, respectively.

25 These ridges may be joined at the heel, or disconnected, as desired. The sunk portion between the ridges is made with sloping sides and rounding bottom, so as to prevent any dirt from lodging between. *c* are the usual

perforations for securing the shoe with nails 30 to the hoofs. The bearing formed by the ridges is even all around, and is made sharp enough to perform the function of calks. For gaining all the desired benefits of the shoe, I make the same of steel, of proper malleability 35 to allow of its being fitted to any horse's foot.

The advantages my shoe has shown in practice are that it lasts fully one month in any kind of work without being removed. It makes it impossible for any horse to injure itself in 40 interfering. It will effectually prevent slipping on ice, snow, or hard and slippery ground, and it also obviates the necessity of sharpening, as the double ridge will last until the shoe is worn out.

45 What I claim as my invention is—
In a horseshoe, the combination of the two ridges *a b*, formed upon the sole of the shoe, and following the inner and outer contour thereof, with the intervening sunk portion, 50 which is formed with sloping sides and rounding bottom, substantially as and for the purposes described.

MAX CASPARI.
